UNITED STATES PATENT OFFICE.

GEORGES LE DOCTE, OF BRUSSELS, AND ARMAND LE DOCTE, OF GEMBLOUX, BELGIUM.

PRESS FOR BEET-PULP AND THE LIKE.

1,004,283.

Specification of Letters Patent. Patented Sept. 26, 1911.

Application filed June 30, 1910. Serial No. 569,775.

To all whom it may concern:

Be it known that we, GEORGES LE DOCTE and ARMAND LE DOCTE, both subjects of the King of Belgium, residing at Brussels and 5 at Gembloux, in the Kingdom of Belgium, have invented new and useful Improvements in Presses for Beet-Pulp and the Like, of which the following is a specification.

10 Our invention relates to presses for beet pulp, employed in sugar works and distilleries and is for the purpose of remedying certain well known inconveniences found in beet pulp presses hitherto used, which principally consist in the entire or partial evacuation of the press at the time of an accidental modification in the physical state of the substance to be pressed; in the impossibility of automatically reestablishing the 15 normal action of the press in case of complete evacuation, and in the impossibility of regulating the evacuation of the pressed material at different points of the outlet opening of the press.

20 With said purposes in view, the invention consists in the combination with the circular evacuation opening of an ordinary pulp press, of an auxiliary outlet regulator which exercises a variable and regulatable action 25 at different points of the orifice and prevents the evacuation of the material treated as long as a pressure determined in advance is not reached. In carrying the invention into practice this regulator is preferably 30 constituted by a series of shutters mounted on hinges, provided with regulatable counter-weights and arranged so as to close, when in the state of rest, the circular outlet 35 opening of the press and to consequently 40 oppose a regulatable resistance to the free escape of the material pressed.

The annexed drawing illustrates by way of example, a construction of the invention.

Figure 1 diagrammatically illustrates in 45 vertical section the essential parts of an ordinary pulp press of a known kind. Fig. 2 is a horizontal section on line A B of Fig. 1 and shows a regulator constructed according to the invention in its position of in- 50 action.

The press shown in Fig. 1 comprises a perforated sheet metal cylinder *a* in which

a cone *c* provided with paddles *d* rotates. The material to be pressed, introduced at the top of the press by means of the funnel 55 *e*, is carried along by the cone and paddles and is pressed between the cone and the perforated cylinder *a* which is surrounded by the jacket *b* provided with an outflow orifice for the water extracted. The material pressed and freed from this water, is evacuated at the lower part of the apparatus by the annular opening *o* constituted by the space separating the extremity of the perforated cylinder *a* from a conical disk *n* 60 which forms an extension of the rotary cone *c* and acts as a support and a bearing for the same. The opening *o* can be varied in the ordinary manner that is to say, it can be increased or diminished by lowering or 65 raising the disk *n* by means of a suitable mechanical device not shown.

As is well known, when the opening *b* reaches a certain amplitude very slight differences in the physical state or composition 75 of the matter treated in the apparatus are often sufficient to prevent the pressure being produced. In this case, the mass or pulp has no longer sufficient resistance at the outlet and simply slides along the cone *c* and 80 escapes through the opening *o* without being pressed. This happens for instance when the pulp has become too soft by reason of extraction of sugar at too high temperature or from cessation of the work of extraction 85 by having maintained the pulp too long in maceration or when the pulp is made from damaged beet, or when it is introduced into the press at too high a temperature. It also happens when the feed is stopped that the 90 press runs completely emptied unless the workman in charge stops the rotation in time. A fresh feed is then not sufficient to reestablish the normal operation and the material introduced simply slides to the bot- 95 tom of the press and escapes by the opening *o* without having been submitted to any pressure. To remedy these inconveniences and further to allow the state of dryness of the pressed pulp to be regulated at all points 100 of the annular outlet *o* so as to render the composition of all the pulp produced uniform, in the construction shown a series of controlling elements are arranged around the

outlet orifice σ . Each element comprises an immovable part h , fixed by bolts on the exterior jacket b , and a shutter v connected to the part h by a hinge i . The shutter v is provided with a rod t carrying a cast counterweight p provided with a set screw. The counterweight can slide on the rod t and be fixed at any place thereon. The various shutters are arranged side by side on the circumference of the jacket b and are of slightly tapered shape so that in the state of rest, they almost entirely close the annular outlet σ . The rod t provided with the counterweight p holds the corresponding shutter v against the extremity of the conical disk n at a variable pressure according to the position of the counterweight. Each shutter may be provided with a hook engaging in an eye fixed on the jacket b and allowing of maintaining it completely raised that is to say, to leave the corresponding part of the outlet opening σ entirely free, when this position is considered useful for obtaining a desired result. It can be easily understood that the application of an outlet auxiliary regulator of this kind procures the following advantages:

1. The complete or partial evacuation of the press cannot take place when the feed is regular, the outlet opening being never completely free by reason of the obstacle formed by the elements of the regulator of outflow which only open gradually, and more or less completely by the pressure of the evacuated pulp and by the greater or less quantity of this pulp present at any spot of the outlet. The matter cannot then escape freely without pressure; there must be a preliminary pressure sufficient to overcome the resistance opposed to the outflow by the elements of the regulator and this regular and continuous obstacle has the effect of constantly maintaining the press in a condition of normal function.

2. In case of complete evacuation of the press by failure of the feed, all the elements of the outlet regulator are in a state of rest, that is to say, in the position in which they completely close the outlet opening σ . The recharging of the press and its normal function is automatically reestablished, no evacuation being able to take place before the interior pressure has reached a sufficient degree to overcome the resistance produced by the different elements of the outlet regulator.

3. By suitably regulating the outlet opening σ as well as the degree of action of the elements of the regulator according to the condition of the material evacuated to the different positions of these elements, the composition of the matter pressed can be regulated as one can increase or lessen as

desired the outflow at each part of the press corresponding to each of the elements of the regulator.

What we claim is:

1. In combination, a press of the kind described provided with an evacuation opening and with an outlet regulator, and an auxiliary outlet regulator operatively associated with said opening, said auxiliary regulator being responsive to a predetermined pressure within the press whereby the evacuation of the material at the opening is prevented as long as said predetermined pressure is not reached.

2. In combination, a press of the kind described, provided with an evacuation opening and with an outlet regulator, and a plurality of controlling elements arranged around the evacuation opening and forming an auxiliary outlet regulator, each of said elements acting independently and each of said elements being responsive to a predetermined pressure within the press whereby a variable pressure can be secured at different points of the opening.

3. In combination, a press of the kind described provided with an evacuation opening and with a conical disk coöperating with said opening, a plurality of controlling elements, arranged around the evacuation opening, and means coöperating with said controlling elements whereby the action of said controlling elements can be varied at will.

4. In combination, a press of the kind described provided with an evacuation opening and with a conical disk coöperating with said opening, and pivotally mounted elements and weights acting on said elements whereby the evacuation opening is normally closed by said elements.

5. In a press for beet-pulp the combination of an outer jacket provided with an outlet opening at its lower end, a metal cylinder in said jacket, a cone rotating in said cylinder, a conical disk adapted to vary the section of the outlet opening, a plurality of shutters pivotally mounted on the outer jacket, counterweights acting on said shutters whereby said shutters are adapted to offer a variable resistance to the discharge of the material through the outlet opening and means for putting said shutters out of action each independently of the others.

6. In a press for beet pulp the combination of an outer jacket, a perforated metal cylinder in said jacket, a discharge opening at the lower end of the outer jacket and perforated metal cylinder, a cone adapted to be rotated in the perforated metal cylinder, a conical disk placed coaxially with the cone in the discharge opening, a plurality of shutters arranged around the discharge opening, fixed parts attached to the outer

jacket and to which the shutters are pivotally connected, a rod projecting from each shutter a counterweight adapted to be displaced along said rod and acting to hold 5 the corresponding shutter in a position in which the corresponding portion of the discharge opening is closed and means for placing each shutter out of action.

In testimony whereof we have signed our names to this specification in the presence of 10 two subscribing witnesses.
